UNITED STATES PATENT OFFICE.

EDGAR DUNCOMBE EDDY AND ALBERT WELLINGTON CAMPBELL, OF TORONTO, ONTARIO, CANADA, ASSIGNEES TO EDDY SEED CLEANERS, LIMITED, OF TORONTO, CANADA, A JOINT-STOCK COMPANY.

COMBINED WASHER AND DRIER OF THE CONTINUOUS CENTRIFUGAL TYPE.

Application filed December 12, 1924. Serial No. 755,542.

Our invention relates to improvements in combined washers and driers of the continuous centrifugal type and the object of the invention is to throw off the liquid with which the material to be dried is mixed, and, if desired, subsequently to wash such material with water and throw off the washing water from the material so that the material is dispelled from the machine in a substantially dry state.

A further object is to devise means for keeping the rotating screen clean so that it will not become wholly or partially clogged and thereby interfere with the effectiveness of the drying action.

A still further object is to devise means for conveying the material being treated from the intake to the discharge end of the machine and for scraping the screen in which it will be possible to actuate the scraping means at more nearly the speed of the screen or at any suitable relative speed, thus reducing wear on both the screen and scrapers while maintaining the desired scraping action.

Another object is to make possible the treating of small particles such as fine seed, crystals and the like continuously instead of by the batch methods, thus effecting an economy in power, labour and time.

Our invention consists of a combined washer and drier constructed and arranged all as hereinafter more particularly described and illustrated in the accompanying drawing in which:

Fig. 1 represents a vertical longitudinal section through the machine.

Fig. 2 is a vertical section taken on the line 2—2 Figure 1.

Fig. 3 is a vertical section taken on the line 3—3 Figure 1.

Fig. 4 is an enlarged vertical section through the line 4—4, Figure 1.

Fig. 5 is a plan view of the scrapers, and conveyor flights.

Fig. 6 is a perspective detail of the means for supporting the screen contacting scrapers, and

Fig. 7 is a plan view of one of such scrapers.

Like characters of reference indicate corresponding parts in the different views.

1 is the casing of the machine. 2 is the longitudinal shaft extending therethrough and journalled on the bearings 3 disposed exteriorly thereof on the base 4. 5 is a drive

pulley on the shaft 2. The end of the shaft 55 remote from the driving pulley 5 is end-bored to constitute the hollow interior 6 which is connected intermediately of its length with a transversely extending nozzle 7, the hollow end of the shaft 2 being connected by the 60 gland 8 with the water pipe 9 which is connected with a water supply.

10 is a circular spider provided with the hollow boss 11 rotatable on the shaft 2. 12 is an opposed hollow boss rotatable on the shaft 65 2 in the vicinity of its other end and provided with the disc 13 which is connected by means of the bolts 14 with the circular end plate 15. 16 is a cylindrical cage extending between the end plate 15 and the spider 10 and adapted 70 to carry the screen 17 which is preferably of the perforated metal type although this could be a metal gauze screen if so desired.

18 is a circular opening in the end of the casing 1, the edge of which is inserted into the 75 groove 19 in the stationary annular member 20 which is freely mounted on the boss 12 and through which is inserted the inlet pipe 21 by means of which the material to be dried 80 is introduced into the interior of the screen 17.

The boss 12 is provided with the driving pulley 22. 23 and 24 are chutes depending from the casing 1 on each side of the vertical partition 25, the inner edge of which is inserted into a channel 26 in one of the annular 85 members 27 of the cage 16.

28 is an annular collecting space formed in one end of the casing 1 and communicating through the spider 10 with the interior of the cage 16 and provided with a tangential 90 discharge chute 29.

30 are spaced apart bosses secured to the shaft 2 on each side of the nozzle 7 and provided with the opposed radially extending scraper and conveyor flight carrying arms 95 31. 32 are longitudinal scraper carrying rods journalled in bearing brackets 33 at the extremities of the arms 31. 33^x are transversely extending arms formed integrally with the bearing brackets 33 upon which the conveyor flights 36 are mounted by having their brackets 34 connected to a bar 35 which is carried by the arms 33^x. The flights 36 are not adapted to contact with the inner surface of the screen 17 but are positioned a small distance therefrom in order to remove the bulk of material from the screen and for this purpose these flights are set at an incli- 100 105

nation so that they will impart a spiral movement to the material moved and gradually force it towards the discharge end of the cage 16, as will hereinafter appear.

5 38 are resilient members extending transversely from the rods 32 in the opposite direction to the arms 33*. Each of these resilient members is secured to a scraper holding plate 40. Scrapers 41 constructed of wood, 10 celeron or other suitable material are secured between the plates 39 and 40, and each scraper has a vertically extending central slot 42 and inwardly extending lateral slots 43 into which are inserted the opposed lugs 15 44 on the scraper holding members 39 and 40. A lug 44 is provided on opposite ends of the members 39 and 40 and registers with an inwardly extending slot 45 in the opposite scraper holding member.

20 The free ends 46 of the resilient members are threaded to receive the nuts 47 which when screwed up force the member 40 towards the member 39 and thus grip the scraper 41 between such member 40 and the member 39, 25 the slot 42 on each scraper 41 being provided to enable the scraper to straddle the resilient member and thus provide means for readily removing the scraper when it becomes worn. The scrapers 41 are designed to contact with 30 the internal face of the screen 17 and thus keep the screen from clogging and remove from it the particles of material not removed by the flights 36. They are set at the same inclination as the flights 36 in order to gradually force the material towards the discharge end of the screen. These scraping elements may be replaced by brushes of wire 35 or other suitable material if desired.

40 48 is a forked member secured to each rod 32 intermediately of its length and extending inwardly towards the shaft 2. 49 are outwardly extending lugs secured to the shaft 2 and having their extremities extending between the forked end of the forked member 45 48. 50 is an adjusting screw threaded through one of the legs of the forked member 48 with which the lug 49 is adapted to coact, said adjusting screw 50 being provided with the handle 51. This mechanism is provided 50 to vary the pressure of the scrapers 41 on the screen 17. The adjusting screws 50 through the spring members 38 limit the pressure of the scrapers 41 on the screen caused by centrifugal force.

55 The operation of our device is as follows:

The screen 17 mounted on the cage 16 is rotated by means of the drive pulley 22 through the boss 12, disc 13 and the plate 15 at a greater speed than the shaft 2 is rotated 60 by the pulley 5. As the shaft 2 carries the flights 36 and scrapers 41 it will be seen that such flights and scrapers are rotated at a slower speed than the screen, and consequently owing to this relative motion between the screen on one part and the flights and scrap-

ers on the other part, the material being treated will be conveyed from the intake to the discharge end of the cylindrical screen and a scraping action will be imparted by the scrapers 41 on the internal face of the screen. 70 As the screen rotates in the direction indicated by the arrow in Figure 4 the bulk of the particles of material and dirt therewith that is clinging to the screen will be removed off by the flights 36, leaving a certain amount 75 of finer particles still on the screen. This will occur due to the fact that the flights 36 do not contact with the screen but when the particular portion of the screen is further rotated it will come into contact with the scrapers 41, which will remove such fine particles 80 from the screen and thus prevent it from becoming clogged. Due to the fact that the flights 36 and scrapers 41 are pitched at an angle, a spiral movement is given to the material on the screen which gradually works it along towards the discharge end, it being understood that a plurality of sets of flights and scrapers are used in the construction 85 above referred to.

90 The material mixed with the liquid is introduced through the inlet pipe 21 into the interior of the screen and owing to the centrifugal action due to the rotation of the screen the liquid is thrown out therethrough into 95 the casing 1 and discharged through the chute 23, the material being thus partially dried.

In order to wash any remaining liquid 100 from the material, water is introduced through the nozzle 7 which rotates with the shaft 2 and the material is sprayed therewith. As the flights and scrapers move the material along towards the discharge end of the screen the washing water is thrown off 105 from the material by centrifugal action and discharged through the chute 24, the material being discharged from the discharge end of the screen through the spider 10 and into the annular space 28 and finally discharged 110 through the chute 29 by means of which it is carried to any convenient place.

If it is desired to regulate the pressure of the scrapers 41 on the screen 17 the adjusting screw 50 is screwed down closer to the lug 49 and consequently the swing of the scrapers 41 about the rods 32 is limited. Such scrapers tend to swing outwardly due to 115 centrifugal action imparted to them by the rotation of the shaft 2.

A combined washer and drier constructed according to our invention is particularly applicable for drying seeds and can be used in connection with the seed separating apparatus described and claimed in United States 125 Patent #1,452,457 issued April 17th, 1923, wherein the inlet pipe 21 would be connected to the seed discharge of such separating device.

120 It is found in practice that when the seeds 130

are discharged from the chute 29 they usually do not contain over 1% more moisture than when delivered to the separating apparatus from the seed houses or farms, it being understood that the seeds are delivered to my washer and drier from the seed separator in a substantially wet condition.

Although we have described our device as particularly applicable to the drying of seeds, especially fine clover seeds it can also be used for drying many kinds of crystals or other material having large surface moisture, such as sugar, salt and wet grains.

Our device makes possible the treatment of small particles continuously instead of by the batch method and in addition to partially drying the material treated, if desired, washes any liquid mixed with it therefrom and throws off the washing water.

The use of the non-contacting conveyor flights 36 in conjunction with the scrapers 41 makes it possible to rotate the scraping and conveying mechanism at more nearly the speed of the screen and yet secure the desired conveying and scraping effect. This is due to the fact that the conveyor flights remove the bulk of the material from the screen and thus lighten the work of the scrapers with the consequent decrease in wear on both screens and scrapers.

The device is susceptible to use as a drier alone by eliminating the use of the washing water in cases where it is not necessary to wash the material passing through the device.

What we claim as our invention is.

1. In a device of the character described, the combination with a shaft and means for driving the same, of a cylindrical screen rotatably mounted on the shaft, independent means for driving the screen, members with radially extending arms secured to the shaft, longitudinally extending rods rotatably secured to the ends of the arms, screen non-contacting conveyor flight elements secured to the arms and screen contacting scraper elements secured to the rods, said non-contacting elements functioning prior to the contacting elements.

2. In a device of the character described, the combination with a shaft and means for driving the same, of a cylindrical screen rotatably mounted on the shaft, independent means for driving the screen, members with radially extending arms secured to the shaft, longitudinally extending rods rotatably secured to the ends of the arms, screen non-contacting conveyor flight elements secured to the arms and screen contacting scraper ele-

ments resiliently secured to the rods, said non-contacting elements functioning prior to the contacting elements.

3. In a device of the character described, the combination with a shaft and means for driving the same, of a cylindrical screen rotatably mounted on the shaft, independent means for driving the screen, members with radially extending arms secured to the shaft, longitudinally extending rods rotatably secured to the ends of the arms, screen non-contacting conveyor flight elements secured to the arms and screen contacting scraper elements resiliently secured to the rods, said non-contacting elements functioning prior to the contacting elements, both scraper and flight elements set at an angle to the longitudinal axial line of the screen.

4. In a device of the character described, the combination with a shaft and means for driving the same, of a cylindrical screen rotatably mounted on the shaft, independent means for driving the screen, members with radially extending arms secured to the shaft, longitudinally extending rods rotatably secured to the ends of the arms, screen non-contacting conveyor flight elements secured to the arms and screen contacting scraper elements resiliently secured to the rods, said non-contacting elements functioning prior to the contacting elements, both scraper and flight elements set at an angle to the longitudinal axial line of the screen, and coacting means between the rods and shaft for controlling the pressure of the screen contacting scraper elements on the inner surface of the screen.

5. In a device of the character described, the combination with a shaft and means for driving the same, of a cylindrical screen rotatably mounted on the shaft, independent means for driving the screen, members with radially extending arms secured to the shaft, longitudinally extending rods rotatably secured to the ends of the arms, screen non-contacting conveyor flight elements secured to the arms and screen contacting scraper elements resiliently secured to the rods, said non-contacting elements functioning prior to the contacting elements, both the scraper and flight elements set at an angle to the longitudinal axial line of the screen, an inwardly extending forked member secured to each rod, an outwardly extending lug on the shaft coacting with each forked member, and an adjusting screw on each forked member adapted to coact with its shaft lug.
